UNITED STATES PATENT OFFICE.

THOMAS S. POWERS, OF ESSEX, CONNECTICUT.

DESIGN FOR A COFFIN-HANDLE.

SPECIFICATION forming part of Design No. 15,562, dated November 18, 1884.

Application filed September 3, 1884. Term of patent 7 years.

To all whom it may concern:

Be it known that I, THOMAS S. POWERS, of Essex, in the county of Middlesex and State of Connecticut, have invented a new and Improved Design for a Coffin-Handle, of which the following is a full, clear, and exact description.

My design for a coffin-handle consists in an ornamental configuration of the handle at different points in its length, substantially as hereinafter described, and shown in the accompanying drawing, which represents a longitudinal view of a coffin-handle embodying my design. The handle throughout is of a rounded configuration in transverse section. Its center portion, *a*, is of straight cylindrical form, from whence the handle is of like configuration in opposite directions, each of such extended end portions consisting of a tapering, rounded, and concave molding, *b*, adjoining each end of the cylindrical portion *a*, followed in regular order or succession by an ovolو molding, *c*, a straight cylindrical portion, *d*, an ovolو and ogee molding, *e f*, a circular band or fillet, *g*, circular grooved molding *h*,

outwardly-tapering concave moldings *i k*, and a terminal tapering tip, *l*, having an ogee and rounded profile, with straight conical extremity.

Having thus fully described my invention, I claim as new and desire to secure by Letters Patent—

The within-described design for a coffin-handle, having a rounded configuration throughout its length, which consists of a straight cylindrical center portion, *a*, and opposite end longitudinal extensions, each composed of a tapering, rounded, and concave molding, *b*, an ovolو molding, *c*, a straight cylindrical portion, *d*, an ovolو and ogee molding, *e f*, a circular band or fillet, *g*, a circular grooved molding, *h*, outwardly-tapering concave moldings *i k*, and a terminal tapering tip, *l*, of an ogee and rounded profile, with straight conical extremity, as shown.

THOMAS S. POWERS.
